(57) **CLAIM**

I claim the ornamental design for a sailboat, as shown and described.

DESCRIPTION

FIG. 1 is a side view of the sailboat carried by a trailer with its keel raised and its mast lowered.

FIG. 2 is a side view of the sailboat carried by a trailer with its mast raised.

FIG. 3 is a starboard side view of the keel system taken as a section 3—3 in FIG. 4.

FIG. 4 is a front elevation of the keel system taken as a section 4—4 in FIG. 1; and,

FIG. 5 is a side view of the sailboat without a trailer showing a torpedo shaped keel ballast below the boat hull.
